UNITED STATES PATENT OFFICE.

ERICK J. JOHNSON, OF CHICAGO, ILLINOIS.

DAMPER FOR FIREPLACES.

SPECIFICATION forming part of Letters Patent No. 509,911, dated December 5, 1893.

Application filed February 21, 1893. Serial No. 463,173. (No model.)

To all whom it may concern:

Be it known that I, ERICK J. JOHNSON, of Chicago, in the county of Cook and State of Illinois, have invented a new and Improved 5 Damper for Fireplaces, of which the following is a full, clear, and exact description.

The invention relates to dampers such as shown and described in the Letters Patent No. 463,333, granted to me November 17, 1891.

10 The object of the present invention is to provide a new and improved damper for fireplaces, which is simple and durable in construction, very effective in operation, and arranged to conveniently swing the damper plate into an angular position in the throat of the fireplace, and to support it automatically in that position.

15 The invention consists of a cam adapted to engage the pivoted damper plate, to swing the same up or down in the throat of the fireplace and to lock it in position.

20 The invention also consists of certain parts and details and combinations of the same, as will be fully described hereinafter and then 25 pointed out in the claims.

Reference is to be had to the accompanying drawings forming a part of this specification, in which similar letters of reference indicate corresponding parts in all the figures.

30 Figure 1 is a transverse section of the improvement as applied. Fig. 2 is an enlarged transverse section of the improvement on the line 2-2 of Fig. 3. Fig. 3 is a sectional side elevation of the same on the line 3-3 of Fig.

35 Fig. 4 is a plan view of the same; and Fig. 5 is a transverse section of the improvement as arranged in an angular throat.

The fireplace A connects by the throat B with the chimney C in the usual manner, the 40 said throat being arranged either horizontally, as illustrated in Fig. 1, or angularly as shown in Fig. 5. In the throat B is arranged a frame D set in the walls of the fireplace and having an opening therein, and provided on top, 45 near the front edge, with lugs E forming bearings for the trunnions F' of the damper plate F adapted to swing up or down to open and close the opening in the frame D, so as to regulate the draft in the fireplace.

50 On the under side of the damper plate F, and near the middle of the same, is arranged a transversely extending rib F² adapted to

be engaged by the rim of a segmental cam G having its hub G' secured on a transversely extending rod H mounted to turn in apertures D' formed in the projection D³ secured on or formed integral with the frame D, at the under side thereof.

The forward end of the rod H passes loosely through an opening in the fireplace frame A' and on the extreme outer end of the said rod is secured a suitable knob or handle H' for conveniently turning the said rod so as to turn the cam G to swing the damper plate F up or down to open and close the opening in the frame D, thus regulating the draft of the fireplace.

When the frame D is applied to a fireplace A² having an angular throat D' connecting with the chimney C', as shown in Fig. 5, then 70 the frame D is set to the angle of the throat and the rod H is then passed through a second set of apertures D² arranged in the projection D³, so that the rod H extends horizontally, as is plainly shown in the said figure. 75

As illustrated in Fig. 3, the peripheral surface of the segmental cam G is formed with a series of notches G² each adapted to form a seat for the rib F², so that when the operator stops turning the rod H, when swinging the 80 plate F upward or downward, then the rib seats itself in the corresponding notch, thereby locking the cam in place and at the same time supporting and locking the plate F in an angular position.

It is understood that the center of the segmental cam G is eccentric to the center of the rod H on which the cam is secured, and the cam is adapted to engage, with its outer end, a lug F³ projecting from the under side of the 90 plate F at the outer end of the rib F², so that when the plate F is in its uppermost position, as shown in Fig. 2, the lug F³ and the rib F² engage the rim of the cam at the same time.

In order to prevent disengagement of the 95 cam G, I provide a rod I, which extends over the lug F³ and through the cam G to a lug F⁴ secured on the plate F near its center line, as is plainly shown in Fig. 2.

In order to accommodate the inner end of 100 the rod H at the time the frame D is set in the angular throat D', as shown in Fig. 5, I provide the plate F with a recess F⁵ arranged on the under side and adapted to receive the

inner end of the rod H at the time the plate F is closed or fully seated on the frame D.

It will be seen that by the arrangement described the cam G not only serves to impart an up and down swinging motion to the plate F, but also to lock the plate F in any angular position it may be in at the time the operator stops turning the knob or handle H' of the rod H.

Having thus fully described my invention, I claim as new and desire to secure by Letters Patent—

1. The fireplace damper F provided on its under side with a transverse rib F², a lug F³ at right angles to the outer end of said rib and the guide rod I, substantially as set forth.

2. The damper operating cam G in the form of an open segment provided on its curved edge with teeth G² and having an aperture G' to receive the operating rod, substantially as set forth.

3. The combination with the open frame and the damper hinged thereto and provided on its lower face with a transverse guide rod or loop I, of the operating rod provided at its inner end with an open segmental cam through which said rod or loop I passes and said cam engaging the lower face of the damper, substantially as set forth.

4. A damper for fireplaces, comprising a pivoted damper plate provided on its under side with a transversely extending rib, and a cam mounted to turn and engaging the said rib to impart a swinging motion to the damper plate, the rim of the said cam being formed with notches forming seats for the said rib, substantially as shown and described.

5. A damper for fireplaces, comprising a pivoted damper plate provided on its under side with a transversely extending rib, a cam mounted to turn and engaging the said rib to impart a swinging motion to the damper plate, and a fixed rod held on the said pivoted damper plate and passing through the said cam to prevent disengagement of the latter from the damper plate, substantially as shown and described.

6. A damper for fireplaces, provided with an open frame adapted to be set in the throat of the fireplace and formed at its under side with a projection having sets of apertures forming bearings for the damper rod, substantially as shown and described.

ERICK J. JOHNSON.
